Everett Brumaghim,

INVENTOR

BY *Victor J. Evans*

ATTORNEY

UNITED STATES PATENT OFFICE

EVERETT BRUMAGHIM, OF HONOLULU, TERRITORY OF HAWAII

PRINTING PEN

Application filed October 16, 1929. Serial No. 400,049.

My present invention has reference to a lettering pen of the type employed for round writing that is, the printing of art letters such as those of the Old English type, Chinese 5 printing and the like.

The object of the invention is the provision of a pen for this purpose whose blades or nibs are of celluloid which renders the same non-corrosive and which yields the desired 10 amount of flexibility, the said nibs being held in the pen holder by a plug of a novel construction which permits of the nibs being fully inserted in the holder or partly withdrawn therefrom so that the ink space between the nibs and the distance between the 15 points of the nibs can vary.

To the attainment of the foregoing the invention consists in the improvement herein-after described and definitely claimed.

20 In the drawings:

Figure 1 is a side elevation of a lettering pen in accordance with this invention.

Figure 2 is a greatly enlarged sectional view through the lower end of the holder to better illustrate the manner in which the shanks of the pen are engaged and held in the holder by the plug.

Figure 3 is a sectional view on the line 3—3 of Figure 2.

30 Figure 4 is a side elevation illustrating a slight modification.

Figure 5 is a view substantially similar to Figure 2, with the plug in section.

Figure 6 is a sectional view on the line 35 6-6 of Figure 5.

Figure 7 is a perspective view of the plug. Figure 8 is a similar view of one of the

40 The pen blades or nibs are constructed of celluloid and in the showing of Figures 1 to 3 the nibs 1 are joined together at their upper portions and held angularly with respect to each other by a headed rivet 2. The portion of the device beyond the nibs is indicated by the numeral 4, and this portion is formed with a bifurcated extension 5 that is designed to be received in oppositely disposed angularly arranged longitudinally extending grooves 6 in a plug member 7. The plug member is inserted for frictional engagement

with the wall of an opening or bore 8 in the lower portion of the holder 9. The holder is preferably round and its outer end is reinforced by a flanged metal ring 10 which will prevent the splitting thereof.

The second and preferred form of the invention includes a holder 11 similar to that above described. In this instance two celluloid blades or nibs 12 are employed, each having its edges tapered to its outer end but, of course, the said outer or active end of the nibs may be of any desired width. Each nib on its upper end is centrally formed with an extension in the nature of an arm 13, the said arms designed to be received in oppositely disposed grooves in a plug 14 that is inserted in and frictionally engages with the wall of an opening in the pen holder 11.

My improvement is of an extremely simple nature but presents a device which may be cheaply manufactured, which is strong, which will be found thoroughly efficient in practical use, which is non-corrosive and wherein the pen nibs may be readily withdrawn from the holder in the cleaning thereof. 70 75

Especially in the construction disclosed in Figures 5 to 8 it will be noted that the pen nibs may have their extensions or arms 13 either wholly or partly inserted in the grooves of the plug 14, so that the nibs may be properly adjusted with respect to each other and ink held between the nibs will be permitted to freely and slowly flow therefrom in accordance with the purpose of the user. 85

Having described the invention, I claim:

1. A lettering pen as herein described having celluloid nibs provided with extensions, a holder for the nibs having an opening to receive said extensions therein, a plug received in and frictionally contacting with the holder and said plug having angularly disposed longitudinally arranged grooves in the opposite sides thereof to receive therein and to hold the nib extensions. 95

2. A lettering pen as herein described having celluloid nibs provided with extensions, a holder for the nibs having an opening to receive said extensions therein, a plug received in and frictionally contacting with

the holder and said plug having angularly disposed longitudinally arranged grooves in the opposite sides thereof to receive therein and to hold the nib extensions, and a reinforcing metal ring for the outer end of the holder.

In testimony whereof I affix my signature.
EVERETT BRUMAGHIM.
